UNITED STATES PATENT OFFICE.

CORNELIUS EVAN JOHNSON, OF GRAND RAPIDS, MICHIGAN.

DEVICE FOR REMOVABLY HOLDING SHEETS OF PAPER AND THE LIKE.

Application filed January 12, 1922. Serial No. 528,666.

To all whom it may concern:

Be it known that I, CORNELIUS EVAN JOHNSON, a citizen of the United States, residing at Grand Rapids, in the county of Kent and State of Michigan, have invented new and useful Improvements in Devices for Removably Holding Sheets of Paper and the like, of which the following is a specification.

10 The present invention relates to devices for removably holding sheets of paper and the like; and its object is to provide such a device wherein the sheets may be readily inserted and securely held and from which 15 they may be as readily removed when desired.

This object is attained by, and the invention finds preferable embodiment in, the structure or structures particularly described 20 in the body of this specification and illustrated by the accompanying drawings, viz.:—

In Figures 1, 2, 3, 4, 5 and 6, one embodiment of my invention is shown.

25 Figure 1 illustrating an opened pair of covers flexibly connected and showing a top plan view of a device for removably holding sheets of paper and the like;

30 Figure 2 is a sectional view of the same taken on a plane corresponding to line 2—2 of Figure 1, but showing the covers closed;

Figure 3 is a like view thereof taken on line 3—3 of Figure 1;

35 Figure 4 is a top plan view of the base of said device and connected parts;

Figure 5 is a view in perspective of the spring member whereby the sheets are held in place; and

40 Figure 6 is a fragmentary view showing a binding post of the device;

Figures 7, 8, 9, 10 and 11 illustrate a modified form of my device;

Figure 7 being a top plan view thereof with covers opened:

45 Figure 8 is a top plan view of the base of the same;

Figure 9 is a sectional view of the device taken on a plane corresponding to line 9—9 of Figure 7, but showing the covers closed;

50 Figure 10 is a like view of the same taken on a plane corresponding to line 10—10 of Figure 7; and

Figure 11 is a top plan view of the spring member whereby the sheets are held in place.

55 In the following illustrative forms of my invention, a device for removably holding

sheets 1 of paper, etc., is shown (and which may be provided with covers 2, 3 flexibly connected at 4), which comprises a base carrying one or more binding posts adapted 60 to be thrust through suitable registering openings 5 in the sheets, each post having a keeper adjacent its outer end; and comprises also a spring member having an aperture or apertures into which the post or posts may 65 be thrust endwise when said member is sprung outwardly from the base, this member being then movable edgewise to a position in which it is held against reverse or releasing movement.

70 In the construction seen in Figures 1, 2, 3, 4, 5 and 6, the base 6 carries the binding post 7 provided adjacent its upper end with a keeper in the form of an annular groove 8. The sheets 1 are held in the device on 75 said post which passes through their registering openings 5 and are retained thereon by the flat spring member or strip 9. This spring member has an aperture therethrough having a wide portion 10 (or as shown, a 80 pair of such portions) and a second and narrower portion 11 between the portions 10. The post may be freely thrust through either of said portions 10, and the member 9 may then be slid edgewise in its longitudinal direction until the keeper—the annular groove—of the post is received into the narrower portion 11, whereupon the part of the member 9 which is adjacent the post is held against springing movement. This spring 85 member has at either end a downwardly or inwardly extending lug 12 engaging the edges of the contents (the sheets 1) held in the device, when the member 9 is in the position seen in Figure 1, said lugs in the flat position of said member thus preventing it from being slid and thus retaining the device's parts in operative holding position relatively to its contents. This member 9 however, being springable, may be sprung at either 90 end outwardly from the contents 1 sufficiently to carry its lug clear of said contents, whereupon said spring member may be slid toward the opposite side of such contents to a position where the wider portion 10 of the aperture registers with the post, whereupon the spring member may be removed.

In again applying the spring member to hold the contents of the device, a wider portion 10 of the aperture is pushed down over 110 the end of the post (one of the lugs 12 then resting on said contents 1), and being sprung

or bowed toward the contents the spring member may be slidably moved endwise until the narrow portion 11 of the aperture is engaged and held in the keeper groove 8 and 5 the lug passes off from the face of the contents and engages the side thereof as particularly seen in Figure 3, whereupon the device is in operative holding position.

In the modified construction seen in Figures 7, 8, 9, 10 and 11, the base 6 carries a pair of binding posts 7¹ formed by cutting the base plate at 13 and bending up tongues whose extremities are bent toward each other to form the hook portions or keepers 14. 10 The spring member 9¹ for retaining the sheets 1 on these binding posts has a pair of elongated slots or apertures 15 through which the posts and their keepers may be freely thrust when the middle of the spring member 15 is sprung or bowed outwardly from the contents 1 sufficiently to permit such operation. When the spring member 9¹ however is released from such sprung or bowed position and lies flat on the contents, it is held 20 in that position by the keepers which then engage its upper surface at the mutually adjacent sides of the two apertures, as particularly shown in Figure 9. In this position either of the posts forms means for retaining 25 the inner side of the aperture in the other post in holding engagement with the spring member.

It will be seen that in either form of the device shown, the spring member 9 and 9¹ is urged by its own elasticity to a straight or unbowed position wherein the lugs 12 of one of the posts 7¹ holds it against the edge-wise movement which would permit of the detachment of the spring members from the 30 keepers.

The invention being intended to be pointed out in the claims, is not to be limited to or by details of construction of the particular embodiment or embodiments thereof 45 illustrated by the drawings or hereinbefore shown or described.

I claim:

1. In a device of the character described: a base carrying a post adapted to be thrust 50 through registering openings in the device's contents and provided with a keeper adjacent its outer end; a spring member having a lug and provided with an aperture having a portion into which the post may be thrust

endwise and a second portion, said member being springably movable relatively to said contents to thrust the post into the first mentioned portion of the aperture and then movable edgewise into a position wherein the second portion of the aperture is held by the keeper against outward springing movement adjacent the post and said member is urged by its elasticity to cause its lug to engage an edge of the said contents to hold said member against reverse edgewise movement. 60

2. In a device of the character described: a base carrying a post adapted to be thrust through registering openings in the device's contents, and provided with a keeper adjacent its outer end; a spring member having a lug and provided with an aperture having a portion into which the post may be thrust endwise and a second portion, said member being springably movable relatively to said contents to thrust the post into the first-mentioned portion of the aperture and then movable edgewise to a position wherein the second portion of the aperture is held by the keeper against springing movement adjacent the post and said member is urged by its elasticity to cause its lug to engage means for holding said member against reverse edgewise movement; means for thus holding the lug against such reverse edgewise movement of said member. 70

3. In a device of the character described: a base carrying a post adapted to be thrust through registering openings in the device's contents and provided with a keeper adjacent its outer end; a spring member having lugs and provided with an aperture having a portion into which the post may be thrust endwise and a second portion, said member being springably movable relatively to said contents to thrust the post into the first mentioned portion of the aperture and then movable edgewise into a position wherein the second portion of the aperture is held by the keeper against outward springing movement adjacent the post and said member is urged by its elasticity to cause its lugs to engage opposite edges of said contents to hold said member against edgewise movement. 90

In testimony whereof I have hereunto set my hand at Grand Rapids, Michigan, this 105 3rd day of January, 1922.

CORNELIUS EVAN JOHNSON.
